By *his Atty.*

UNITED STATES PATENT OFFICE.

THOMAS MANEY, OF LOUISVILLE, KENTUCKY.

GUARD-RAIL FASTENER.

Application filed October 9, 1926. Serial No. 140,592.

My invention relates to an improvement in guard-rail fasteners.

The present invention is an improvement on the structure disclosed in Serial No. 5 116895, filed by me in the U. S. Patent Office on June 18, 1926.

In the present invention, the guard rail is preferably T-shaped, with an enlarged head at the top, presenting a broad guard 10 surface at the opposite edges, and with a relatively small and narrow base which is held rigidly in the chair, the chair embracing the base substantially one entire side of the web, and extending beneath, and 15 connecting to, the lower surface of the head.

The invention presents other features of novelty which will be hereinafter more fully described.

In the accompanying drawings:

20 Fig. 1 is a side elevation;

Fig. 2 is a plan view; and

Figs. 3 and 4 are front and rear views of the chair; and

25 Fig. 5 is a detail view showing the resilient key beneath the chair.

The numeral 1 in Fig. 1 represents the guard-rail. This has a relatively broad and thick head 2, preferably in the form shown with a flat upper surface 3. The purpose 30 of this is to present a broad expanse of surface to the wheel, which is indicated in dotted lines. The web is relatively narrow, and the base 4 is preferably much narrower and thinner than the head 2.

35 The base is fitted more or less closely in a seat 5 in the upper surface of the chair 6, and the chair rests upon the tie-plate 7 against the upturned shoulder or flange 8, it being provided with lugs 9 at each edge 40 which straddle the side edges of the base plate, making the punching of holes in the base-plate unnecessary, and extending beneath the base 10 of the main rail 11, as shown in Fig. 1.

45 The chair is provided with a central brace 12 having strengthening ribs 13 at the edges, which fits and engages the under side of the head of the guard-rail and adjacent the surface of the web as viewed in Fig. 1.

50 Ribs 14 give added strength to the chair. A key 15 is driven into the space between the chair and the base 4 of the guard-rail as illustrated in Fig. 1. Spikes extend through holes 17 and hold the chair and

base-plate securely in position on the tie. 55 Holes 18 on the other end of the tie-plate also receive spikes for holding the base-plate on the tie. The peculiar shape of the guard-rail and chair above-described constitutes an effectual means of guarding the 60 wheels against the possibility of leaving the track.

The chair is preferably grooved on the inner surface as shown at 19 and engages the adjacent edge of the base 10 of the main 65 rail 11.

The key 15 heretofore referred to is preferably resilient and is for the purpose of keying the guard rail in the chair. This key may be made of high tension steel, 70 stamped in the shape shown (see Fig. 5). It may be placed by hand almost to position and then a slight hammer blow will snap it to place. Its value lies first in that it is strong enough to resist all normal 75 strains and that in any event of abnormal strains that will cause injury to more expensive parts, its resiliency will ease such strains. Secondly, it takes up play and prevents movement under vibration of the rail 80 and lessens the noise resulting by such movement. Thirdly, it is kept in place by its own tension.

I claim:

1. A T-shaped guard-rail having a broad 85 thick head, and a relatively narrow base.

2. A T-shaped guard-rail having a broad thick head, and a relatively narrow base, in combination with a main rail, a tie-plate, a 90 chair having lugs adapted to embrace the edges of the tie-plate and engage beneath the base of the main rail, and provided with a seat for the base of the guard-rail, and having an upstanding brace which engages the lower surface of the head of the guard- 95 rail and the adjacent surface of its web.

3. The combination with a tie-plate, a main rail, and a guard-rail, of a chair having lugs which embrace the base of the main rail and the opposite edges of the tie-plate, the chair having a seat to receive the guard-rail provided with a brace which engages the under side of the head and adjacent surface of the guard-rail, and a key 100 inserted between the chair and the base of 105 the guard-rail.

4. The combination with a tie-plate, guard rail and chair, the latter embracing the base

of the guard rail and having a space formed between it and one edge of the guard rail base, of a resilient key inserted in said space and exerting tension upon the guard rail base and chair.

5. The combination of a tie plate, a guard rail, a chair mounted on the tie plate for bracing the guard rail and having a space between it and a portion of the guard rail, and a resilient key inserted in said space for exerting tension on the guard rail and chair.

6. The combination of a tie plate, a guard rail, a chair mounted on the tie plate for supporting and bracing the guard rail, and having a space between it and an edge of the guard rail base, and a resilient key inserted in said space for exerting tension on the guard rail and chair, said key having the ends thereof embracing the opposite sides 20 of the chair.

7. The combination of a guard-rail, a chair for bracing said guard-rail and having a space between it and a portion of the guard rail, and a resilient key inserted in said

space for exerting tension on the guard-rail 25 and chair.

8. The combination of a guard-rail, a chair for receiving the base of said guard-rail and for bracing said guard rail, said chair having a space between it and the top of the 30 base flange of the guard-rail, and a resilient key inserted in said space and exerting tension on the top of the guard-rail base flange and chair.

9. The combination of a tie plate, a main rail mounted thereon, and a chair having lugs on the opposite sides thereof embracing the main rail and the opposite edges of the tie plate.

10. The combination of a tie-plate, a main 40 rail mounted thereon, and a chair mounted on the tie-plate for receiving a guard-rail, said chair having lugs on the opposite sides thereof for embracing the opposite edges of the tie plate and extending beneath a portion of the main rail.

In testimony whereof I affix my signature.
THOMAS MANEY.
